UNITED STATES PATENT OFFICE

1,954,617

PACKAGE OF TAPE AND SEWING THREAD
OR THE LIKE

Albert B. Collingbourne, Elgin, Ill.

Application May 28, 1932, Serial No. 614,067

3 Claims. (Cl. 206—47)

This invention relates to a package of tape and sewing thread, or the like, and has for its object to produce a package, containing the articles specified, having a substantially rectangular shape, smooth outer surfaces and symmetrical in appearance.

Bias tape is usually wrapped about a rectangularly shaped piece of cardboard, forming an elongated, flat and thin package. Sewing thread 10 is usually wound upon cylindrical spools.

One of the objects of my invention is to combine bias tape and sewing thread, matched as to color, in a single, compact package of such form that the contents may be enclosed in a wrapper 15 of transparent material, such as cellophane, without danger of the wrapper becoming torn or broken on account of the irregular contour of the articles composing the package.

Other objects and advantages will be apparent 20 from the following description.

In the drawing:

Fig. 1 is a plan view of a package embodying 25 my invention.

Fig. 2 is a longitudinal sectional view taken on the line 2—2 of Fig. 1.

Fig. 3 is a transverse sectional view taken on the line 3—3 of Fig. 2.

In that embodiment of the invention shown in the drawing, a box-like support consists of a 30 single piece of cardboard folded and assembled to form a top wall 10 provided at one end with a folded in extension 11, a bottom wall 12 provided at one end with an extension 13, and side walls 14 and 15 each provided at one end with a flap 16 and 35 at the other end with a flap 17. The flaps 16 and folded in extension 11 form one end wall of the box-like support, and at the opposite end the flaps 17 form the end wall. The extension 13 is disposed in alignment with the bottom 12 and 40 terminates in an upturned end 18.

The wall 10 is adapted to support a conventional package of bias tape which consists of a flat piece of cardboard 19 about which the tape 20 is wrapped. A label 21 extends around the 45 cardboard 19 and tape 20.

One or more spools of sewing thread 22, having a combined length equal to the width of the support and the tape package thereon, and having a diameter equal to the combined heights of 50 the support and tape package, are arranged on the extension 13, between the flaps 17 and end wall 18. Finally a wrapper 23 of transparent material is neatly wrapped about the assembled support, tape package and spools.

55 From the foregoing it will be apparent that the

package has opposite surfaces which are substantially parallel to each other, the outer surfaces are flat and smooth, the appearance is neat and attractive and the wrapper of transparent material is not endangered by any part of the contents 60 of the package protruding beyond the surfaces defining the contour of the package.

Changes may be made in details of construction without departing from the scope of my invention and I do not intend to be limited to the 65 exact form shown and described, except as set forth in the appended claims.

I claim:—

1. A package of tape and sewing thread comprising a box-like support, a flat package of tape, 70 substantially the same in area as the top wall of the support, resting on the support, a spool of thread located adjacent one end of the support, and a wrapper enclosing the support, the package of tape and the spool, the diameter of the spool 75 being substantially equal to the combined heights of the support and tape package, and the length of the spool being equal to the width of the support.

2. A package of tape and sewing thread comprising a box-like support provided with an extension at one end of its bottom wall, a flat package of tape, substantially the same in area as the top wall of the support, resting on the support, a spool of thread located adjacent one end of the 80 support on said extension, and a wrapper enclosing the support, the package of tape and the spool, the diameter of the spool being substantially equal to the combined heights of the support and tape package, and the length of the 85 spool being equal to the width of the support.

3. A new article of manufacture comprising a box-like support provided with an extension at one end of its bottom wall, a flat package of tape, substantially the same in area as the top wall 90 of the support, arranged on the support, a spool of thread located at one end of the support on said extension, and a wrapper of transparent material enclosing the support, the package of tape and the spool, the diameter of the spool being substantially equal to the combined heights of the support and tape package, and the length of the 95 spool being equal to the width of the support.

ALBERT B. COLLINGBOURNE. 105
